US0D1082448S

(12) **United States Design Patent** (10) **Patent No.:** **US D1,082,448 S**
(45) **Date of Patent:** **** Jul. 8, 2025**

(54) **FOOD STORAGE CONTAINER**

(71) Applicant: **Zhejiang Fontal Technology Co., Ltd,**
Taizhou (CN)

(72) Inventor: **Shengli Feng**, Taizhou (CN)

(73) Assignee: **Zhejiang Fontal Technology Co., Ltd,**
Taizhou (CN)

(**) Term: **15 Years**

(21) Appl. No.: **29/927,561**

(22) Filed: **Feb. 5, 2024**

(51) **LOC (15) Cl.** **09-07**

(52) **U.S. Cl.**

USPC **D7/629**

(57) **CLAIM**

The ornamental design for a food storage container, as shown and described.

DESCRIPTION

FIG. 1 is a front, right and top perspective view of a food storage container, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the food storage container that form no part of the claimed design.

1 Claim, 8 Drawing Sheets
